SPRING DEVICE

Lynn H. Matthias, Shorewood, Wis., assignor to
 Allen-Bradley Company, Milwaukee, Wis., a
 corporation of Wisconsin

Application March 27, 1939, Serial No. 264,428

4 Claims. (Cl. 175—341)

This invention relates in general to an improved support for coil springs and in particular to a support for a coil spring used as a spring return device on an electromagnetic switch.

Electromagnetic switches depend primarily upon the weight of the armature with its attached parts and the force of the contact springs to return the movable switch part to its normally open position.

In addition to this weight and contact spring force there is added in some instances to secure a more definite and precise opening of the movable part, a return spring.

Heretofore difficulty was experienced in the mounting of a torsion spring in that the movement of the spring on its support incurred a frictional force which caused indefinite opening and a wear of parts.

An object of this invention is to provide an improved form of coil spring support in which excessive friction between the rotatable end turns of the spring and its support is eliminated.

A further object of this invention is to provide a support for a coil spring in which one end of the coil spring is restrained from rotating relative to a mounting spindle and the other end of the coil spring, which end is free to rotate relative to the spindle, is provided with a bearing and shoulder opposing radial thrust and end thrust of the spring. Thus the rotatable end of the coil spring rotates on the spindle free of restraint by the attenuated rotary motion of the turns of the coil spring that do not have bearing contact with the rotatable bearing and shoulder.

A further object of this invention is the utilization of the new and improved coil spring support as a return device for the armature of an electromagnetic switch.

Referring to the attached drawings,

Figures 1 and 2 show a front and side elevation respectively of a magnetic switch in the normally open position;

Figure 3 is a view in perspective of the return spring mechanism;

Figure 4 is an exploded view of the return spring mechanism shown in Figure 3; and

Figure 5 is an enlarged view of an assembly of the return spring mechanism.

The magnetic switch shown in detail in Figures 1 and 2 includes a back supporting frame 1 to which is attached an electromagnet 3, consisting of fieldpiece 4, armature 5, coil 6, stationary contact supports 7—7, and armature return mechanism 24. There is also attached to the fieldpiece 4 a front supporting frame 2 which in

conjunction with the back supporting frame 1 provides the complete support for stationary contact supports 7—7.

The switch operates in a vertical position as shown. The fieldpiece 4 has a lower rectangular opening 13 for the armature 5, an upper rectangular opening 14 for the switch operating member 40 and an opening 41 for the switch coil 6. The switch coil 6 is placed in opening 41 and an armature guide 17 is inserted through opening 13 in the fieldpiece 4 and opening 42 in the coil 6.

The armature guide 17 is held in place in the fieldpiece 4 by means of pin 16 that is attached to the fieldpiece 4 and which passes through slot 15 that is formed in switch operating member 40. The armature 5 is placed in the guide 17 from the bottom with the switch operating member 40 projecting through opening 14.

Rigidly connected to the switch operating member 40 is the cross bar 18 that carries the movable contact members 21—21 each having attached thereto, two contacts 22—22.

Each contact member 21 is spring mounted by means of guide post 19 and spring 20.

The stationary contact supports 7—7 carry the stationary contact members 8—8—8—8 each having attached thereto a terminal 10 and a contact 9.

In order to assist the armature 5 to return to its normal position as shown in Figures 1 and 2 an additional downward force is applied by means of the spring return mechanism 24. This mechanism which embodies the invention is shown in detail in Figures 3, 4 and 5.

A spindle 25, having formed thereon a rivet portion 26, a bearing seat 27, a shoulder 28, and cotter pin hole 29, is attached to the back supporting frame 1 by means of riveting 26. A helical coil spring 30 is placed on spindle 25 with its end 31 in a hole 37 of back supporting frame 1. Bearing 33 is placed on bearing seat 27 and inside of coil spring 30 so that the shoulder 34 of bearing 33 contacts the free end turn of the coil spring 30. A washer 35 and a cotter pin 36 are used to securely hold the coil spring 30 and bearing 33 in place. The movable end 32 of coil spring 30 fits within hole 23 in armature 5.

It is to be noted that the outside diameter of spindle 25 and the outside diameter of bearing 33 are slightly smaller than the inside diameter of spring 30.

The coil spring 30 as formed is so designed that it is preloaded in the normal position as shown in Figures 1 and 2. By providing various

positions such as holes 37 and 37' and the shoulder 39 formed by hole 38, three possible positions for the stationary end 31 of coil spring 30 are provided thus offering control over the force applied by the spring mechanism without altering the design of the spring.

The magnetic switch operates in the usual well known manner. As shown in Figures 1 and 2 the switch is shown in its normal open or deenergized position. When the switch coil 6 is energized the fieldpiece 4 and armature 5 have induced therein a magnetic force that is so directed as to raise the armature 5 until the armature pole faces 12-12 contact the fieldpiece pole faces 11-11. The motion of the armature 5 is transmitted directly to the movable contact structure placing movable contacts 22-22-22-22 in contact with stationary contacts 9-9-9-9.

In the closed or energized position there are three forces directed to lower the armature 5; the weight of the armature and attached parts; the contact springs 20; and the armature return mechanism 24. When the switch coil 6 is de-energized these forces operate to return the armature and movable contacts to the open position.

In the case where a magnetic switch is equipped with normally closed contacts the return spring mechanism is of special importance. In such a switch the stationary contacts 9 are below the movable contacts 22 and spring 20 is mounted on post 19 above movable contact member 21. With the magnetic coil 6 de-energized the engagement of contacts 9 and 22 is then caused by the weight of armature and attached parts plus the force exerted by the return spring 30.

In the operation of the spring return mechanism, the bearing 33 and shoulder 34 are free to rotate on the bearing seat 27 thus providing a surface for supporting the free end of the coil spring 30. This construction eliminates excessive friction and cutting that would take place between the end turns of the coil spring and the spindle 25 if bearing 33 were omitted and the coil spring supported by a rigid spindle. In the disclosed construction, one end of the coil spring is restrained from rotating relative to the spindle and the opposite end is free to rotate relative to the spindle. The bearing 33 and shoulder 34 provide for the complete support of the rotatable end of the coil spring. The bearing and shoulder oppose radial thrust and end thrust imparted to the coil spring 30 by the armature 5 upon movements from one position to another. The free end of the coil spring is thus free to wind and unwind around its supporting spindle free of restraint by the attenuated rotary motion of those turns of the spring that do not have bearing contact with bearing 33.

The coil spring 30, assembled as in the switch device, will have the first turn or so, adjacent end 32 contacting on lower surface of bearing 33, as clearly shown in Figure 5.

With the diameters of the spring, bearing and spindle properly proportioned and with proper clearance between turns of spring, the force applied to the end turn of spring will be substantially transmitted to the remaining turns of spring with little loss due to friction.

It is also to be noted that the disclosed structure minimizes wear by the end turn of the spring against its supporting surface, which wear if allowed to continue might eventually bring into contact with the supporting surface the second and third turns of spring. Under such a wearing condition the friction force between turns

of spring and supporting surface would be excessive and prevent proper operation of the spring return device.

From the foregoing description taken in connection with the accompanying drawings, it will be readily apparent to those skilled in the art that this invention provides a simple and efficient manner of supporting a spring, which support in no wise gives rise to objectionable friction.

10. What I claim as my invention is:

1. The combination of an electromagnet having a base and a movable armature with a spring return device for said armature, comprising a helical coil spring, a spindle and a bearing with a shoulder integral therewith; one end of the spindle being mounted on the base and the other end of the spindle mounting the bearing; said coil spring disposed concentrically on the spindle with one end of the spring attached to the base and restrained from rotating relatively to the spindle; the other end of said coil spring attached to the armature whereby upon movement of the armature said second mentioned end rotates relatively to the spindle; said bearing being rotatable on the spindle and extending sufficiently inside the turns at the second mentioned end of the coil spring to oppose radial thrust and end thrust of said second mentioned end but not far enough to come into contact with the remaining turns of the spring, whereby, said bearing and shoulder turn with and support the end of the spring attached to the armature free of restraint by the turns of the spring between the bearing and the base.

35. 2. A spring return device for an electromagnet having a base, a fieldpiece mounted on said base, an armature cooperating with the fieldpiece and adapted to move in substantially a straight line; said spring return device comprising a helical coil spring having a plurality of turns, a spindle and a bearing with a shoulder integral therewith; one end of the spindle being mounted on the base and the other end of the spindle mounting the bearing; said coil spring disposed concentrically on the spindle with one end of the spring attached to the base and restrained from rotating relative to the spindle; the other end of said coil spring having means coupling it with the armature whereby upon straight line motion of said armature said second mentioned end rotates relative to the spindle; said bearing being rotatable on the spindle with said shoulder opposing end thrust of said second mentioned end, and said bearing extending far enough within sufficient turns at the end of the spring attached to the armature to oppose radial thrust thereof but not far enough to come into contact with the remaining turns of the spring, whereby, said bearing and shoulder turn with and support the end of the spring attached to the armature free of restraint by the turns of the spring having less relative motion with respect to the spindle than the end turns in contact with said bearing.

60. 3. In a coil spring support the combination of a base member, a spindle attached to the base member, a coil spring having a plurality of turns disposed concentrically on the spindle with one end of the spring attached to the base and the other end free to rotate relative to the spindle, and a bearing with a shoulder integral therewith rotatably mounted on the spindle with the bearing extending sufficiently inside the turns at the free end of the coil spring to maintain the free end of said coil spring concentric with said spin-

dle and to oppose radial thrust of the free end but not far enough to come into contact with the remaining turns of the spring, and with the shoulder opposing the end thrust of the free end, whereby, upon rotary motion of the free end of the coil spring relative to the spindle the bearing supports and rotates with said free end substantially unrestrained by the turns of the spring having attenuated rotary motion.

4. In a coil spring support the combination of a base member, a spindle attached to the base member, a helical coil spring having a plurality of turns disposed concentrically on the spindle with one end of the spring attached to the base

5 and the other end free to rotate relative to the spindle, and a bearing and shoulder rotatably mounted on the spindle with the bearing extending inside and having bearing contact with only a limited number of turns contiguous with the free end of the coil spring and with the shoulder opposing end thrust of the free end, whereby, upon rotary motion of the free end of the coil spring relative to the spindle the bearing and shoulder support and rotate with said free end with the bearing unrestrained by the attenuated rotary motion of the remaining turns.
